UNITED STATES PATENT OFFICE

113,325

DESIGN FOR A COMBINED GOLF BAG AND DRESS SHIRT COMPARTMENT

Edwin J. Hughes, Jr., Larchmont, N. Y.

Application August 19, 1938, Serial No. 79,437

Term of patent 3½ years

To all whom it may concern:

Be it known that I, Edwin J. Hughes, Jr., a citizen of the United States, and resident of Larchmont, in the county of Westchester and State of New York, have invented a new, original, and ornamental Design for a Combined Golf Bag and Dress Shirt Compartment, of which the following is a specification, reference being had to the accompanying drawing, forming a part thereof, and of which Figure 1 is a view in front elevation of a combined golf bag and dress shirt compartment showing my new design; Fig. 2 is a view thereof in side elevation; Fig. 3 is a view thereof in rear elevation with the shirt compartment in partly open position; Fig. 4 is a view thereof in front elevation with the handle for the detachable compartment in exposed position; and Fig. 5 is an opposite edge view thereof showing the exposed handle of Fig. 4.

I claim:

The ornamental design for a combined golf bag and dress shirt compartment, substantially as shown and described.

EDWIN J. HUGHES, JR.
